UNITED STATES PATENT OFFICE

2,002,602

FLASH LIGHT OF CANDLE TYPE

Herman G. Graubner, New York, N. Y., assignor
to National Carbon Company, Inc., a corpora-
tion of New York

Application April 4, 1932, Serial No. 603,187

5 Claims. (Cl. 240—10.64)

The invention pertains in general to flashlights of the candle type and specifically to improvements in the structure of the base and the switching mechanism thereof.

- 5 When the base in such a flashlight is formed of heavy metal it is difficult and expensive to manufacture and when it is formed of light metal, it does not provide enough weight to give stability to the candle. Therefore, one object of this invention is to provide a base for such a flashlight formed of comparatively light easily worked and preferably non-ferrous metal having a filler of heavier metal closely formed therein to give stability to the candle.
- 10 Another object of the invention is to provide a simple, rugged, and reliable switching mechanism having four operating positions: (1) a position in which the lower end of the switch operating member is below the lower edge of the base and the lamp is lighted; (2) a position in which the lower end of the switch operating member is flush with the lower edge of the base and the lamp is not lighted; (3) a position in which the switch operating member is latched with the lower end thereof above the lower edge of the base and the lamp is not lighted; and (4) a position in which the switch operating member is latched with the lower end thereof above the lower edge of the base and the lamp is lighted.
- 15 Other aims and objects are to provide a candle that is cheaper to manufacture, better in appearance, less liable to corrode, and more rugged in structure.
- 20 Other aims, objects, and novel features will be apparent from the following specification and the accompanying illustration, in which

Fig. 1 is a side view of the candle with the lower portion in section to show the structure of the switch and the base.

25 Fig. 2 is a top view of the base shown in Fig. 1 with the battery casing, battery, and bulb removed.

Fig. 3 is a bottom view of the base shown in Fig. 1.

30 Fig. 4 is a vertical section of an alternative form having a unitary base and battery casing in which the switch shown in the former figures is mounted.

In the preferred form of the invention shown in Figs. 1, 2, and 3, the base comprises a relatively thin outer shell 10 of non-ferrous metal, such as brass, having a central opening with the edge thereof turned downward and threaded to provide attaching means 11 for the battery casing and then turned inward to provide a flange 12

to which is secured a switch and battery support to be described presently.

The base 10 is provided with a filler 13 of comparatively heavy metal having the same form as the base and closely fitting therein to give it strength and weight. The outer edge 14 of the base 10 is turned downward and then inward under the filler 13 to securely hold it in place and provide a unitary structure. The filler 13 is provided with a central opening 15 through which the support 11 for the battery casing extends downward. The filler 13 may also be pressed in place and retained by friction, and it may be spaced from the base 10 any convenient or desirable distance such as being flush with the lower edge. Furthermore, the opening 15 may be of such smaller size as to permit free movement of switch operating member 32.

A battery casing 16 is attached to the base 10 by a threaded lower end 17 that fits within the support 11 and the upper end of this casing is provided with conventional means for carrying a lamp bulb 18. This casing is preferably formed of non-ferrous metal, such as brass, the same as the base 10, so that it will not rust during use when the finish is accidentally removed and the casing is exposed to damp air.

The switching mechanism is mounted on a circular dielectric plate 19 secured to the under side of flange 12 by suitable means, such as rivets 20. An inverted U-shaped battery support 21 is mounted upon the upper side of plate 19 by suitable means, such as a rivet 22, and an ear 23, that passes downward through a slot 24 in plate 19 and is then turned outward. A portion of the upper surface of the battery support 21 is sheared out and bent upward to provide a spring 25 that makes contact with one terminal of a battery 26 and provides for variations in its length. Instead of the flat spring 25 others may be employed such as the customary coil spring.

A switch spring 27 is mounted upon the upper side of plate 19 under the battery support 21 by suitable means, such as rivets 28 and 22. Switch spring 27 is electrically connected to battery support 21 by any suitable means as by providing spring 27 with an arm 29 that rests under one leg of the battery support around its attaching rivet 22.

The plate 19 is provided with an armed opening 30 having one end thereof adjacent switch support 12 and the switch spring 27 is positioned above opening 30 and one end thereof is located above flange 12 with which it is normally in contact unless held away by the switch operating

means. This switch spring 27 is provided with a keyhole-shaped slot 31 having the narrow portion thereof in vertical alignment with opening 30 and the enlarged end thereof out of vertical alignment with opening 30.

5 A switch operating member 32 is provided with an annular groove 33 in which the edges of the narrow portion of slot 31 are positioned to hold member 32 in place. Below switch spring 27, 10 spring operating member 32 is provided with a collar 34 that is adapted to pass through the enlarged central portion of armed opening 30 but does not pass through either of the narrower portions or arms thereof. Below 15 collar 34 switch operating member 32 is provided with a reduced portion 35 that is adapted to be moved into either of the narrower portions or arms of opening 30. Below the reduced portion 35, switch operating member 32 extends down- 20 ward a short distance below the lower edge of base 10 when switch spring 27 is in contact with flange 12. The upper end 36 of switch operating member 32 is adapted to pass through the large portion of the keyhole slot 31 in switch spring 27 25 for the purpose of convenience in assembly, and as this larger portion of slot 31 is out of vertical alignment with armed opening 30 after the switch is assembled, switch operating member 32 although being movable in both is securely held in 30 position.

The operation of the switch is as follows:

When the switch operating member 32 is in normal position at the center of opening 30, collar 34 will pass downward into the central portion of this opening and allow switch spring 27 to move downward into contact with flange 12 35 and close the electric circuit through the battery, battery support 21, switch spring 27, flange 12, casing 16, and bulb 18, which is in contact 40 with the upper terminal of battery 26. With the switch operating member in this position the light will be extinguished each time the candle is placed on a flat surface and will be lighted each time it is raised therefrom.

45 When it is desirable to place the switch in a position where the circuit is continuously open, the switch operating member is manually moved into the arm of opening 30 away from flange 12. In this position collar 34 is resting on the edge of opening 30 and switch spring 27 is held out of 50 contact with flange 12 and therefore the circuit is locked open and the lamp will not be lighted when it is raised from a flat surface.

When it is desirable to place the switch in a 55 position where the circuit is continuously closed even though the candle is resting on a flat surface, switch operating member 32 is moved into the arm of opening 30 towards the flange 12. In this position collar 34 is resting upon flange 12 60 and thereby completes the electric circuit between this flange and switch spring 27. Therefore, the lamp will remain continuously lighted until switch operating member 32 is manually moved from this position.

65 In both positions of the switch operating member where the circuit is continuously open and continuously closed the lower end thereof is above the lower edge of base 10 and therefore the switch operating member is not liable to be moved when 70 the candle is placed on a flat surface.

In the alternative form of the candle shown in Fig. 4 the base 36 and battery casing 37 are formed in one unitary part, preferably of metal, in a manner known as die-casting. A threaded portion 38 is provided within the base in which

75 a correspondingly threaded flange 39 is held. This flange carries a switch structure similar or identical with that already described. In this structure, however, flange 39 is removable from base 36 for the purpose of inserting batteries in the battery casing 37.

It is understood that various changes in the form and arrangement of the component parts may be made and that similar and equivalent materials may be substituted for those specified 10 without departing from the spirit of the invention or the scope of the claims.

I claim:—

1. In a flashlight of the candle type having a base provided with a flange, a battery casing carried by said base, a battery within said casing, and a bulb mounted upon said casing; a dielectric plate carried by said flange and provided with an armed opening therein; a battery support secured to said plate; a switch spring having a keyhole-shaped slot therein secured to said plate in electrical contact with said battery support and adapted to make electrical contact with said flange to complete the electric circuit through said battery and bulb; a switch operating member having a groove therein by which it is held in said key hole slot and a collar thereon adapted to pass through the center of said armed opening to rest on the top of said switch plate in one of said arms to hold said switch open, and to 20 rest on said flange in the other of said arms to complete the electric circuit; said member extending below the bottom of said base when in the center of said opening so that said switch is open when the candle is resting on a flat surface. 25

2. In a flashlight of the candle type having a base provided with a flange, a battery casing carried by said base, and a battery and a bulb carried by said casing; a dielectric plate carried by said flange and having an armed opening therein; a battery support carried by said plate and electrically connected to said battery; a switch spring carried by said plate in electrical connection with said battery support, adapted to contact with 40 said flange, and provided with a keyhole-shaped slot therein in alignment with said opening; and a switch operating member retained in said slot and said opening and adapted to cooperate therewith to move said spring to open position when 45 said candle is resting on a flat surface, to be moved in one direction to hold said spring in open position, and to be moved in another direction where it completes the electrical circuit between said spring and said flange. 50

3. In a flashlight of the candle type having a base provided with a flange, a casing carried by said base, and a battery and bulb carried by said casing; a dielectric plate secured to the under side of said flange and provided with an armed 60 opening therein having one end thereof adjacent said flange; a switch spring mounted on the upper side of said plate with a portion thereof overlying said flange adjacent said opening; means electrically connecting said switch spring 65 with one terminal of said battery; and a switch operating member in said opening having a shoulder adapted for being positioned between said switch spring and said flange to complete the electric circuit. 70

4. In a flashlight of the candle type having a base provided with a flange, a casing carried by said base, and a battery and bulb carried by said casing, a dielectric plate carried by said flange and provided with an armed opening therein; 75

- a switch spring carried by said plate, and provided with a keyhole-shaped slot therein; a switch operating member in said opening and said slot, and provided with a groove in which the edges 5 of the narrow portion of said keyhole slot are positioned; the larger portion of said keyhole slot being out of alinement with said armed opening to prevent said switch operating member from being moved therein and disassembled.
- 10 5. In a flashlight of the candle type having a base provided with a flange, a casing carried by said base, and a battery and bulb carried by said casing; a plate carried by said flange and pro-
- vided with an armed opening; a switch spring carried by said plate and adapted to close the electric circuit through said battery and bulb, and a switch operating member in said opening having a collar thereon adapted to pass through the center of said opening to allow said switch spring to move to closed position, to rest upon the edge of one arm of said opening to hold said switch spring in open position, and rest upon said flange in the other arm of said opening to complete the circuit between said switch spring and said flange. 10
